UNITED STATES PATENT OFFICE.

JOHN CHARLIE KING, OF DALBY, AUSTRALIA.

OVERHEAD RAILWAY SYSTEM.

Application filed May 13, 1926. Serial No. 108,830.

This invention relates generally to elevated railway structures, the invention having more particular reference to a novel type of elevated railway structure. The invention 5 has for an object the provision of an improved elevated railway structure of simple construction and arrangement of parts which will not interfere with street traffic, and may also provide for upper and lower tracks.

10 For further comprehension of the invention, and of the objects and advantages thereof, reference will be had to the following description and accompanying drawing, and to the appended claims in which the various 15 novel features of my invention are more particularly set forth.

Fig. 1 of the drawing is a transverse elevational view of my improved elevated railway structure.

20 Fig. 2 is a fragmentary longitudinal view showing the method employed to elevate the tracks.

Fig. 3 is a similar view to Figure 1, but showing four tracks.

25 Fig. 4 is a modification of my improved elevated railway structure as shown in Figure 3.

As here embodied my improved elevated railway structure comprises a frame work 30 consisting of the upright members 10, located at the curb 11 of the street 12, to support the transverse member 13, which is also supported at its extremity 14 and 15 by the buildings B located at the street sidewalk 16, and reinforced by arched or overhead members 17, also provided to support the overhead cross walk 18 and the stairways 19, stairways 20 also being provided extending from the sidewalk 16 to the transverse member 13, which 35 supports the ties 21 and the rails 22 for tracks, and tie members 24 re-inforce transverse members 13 as shown on the accompanying drawing. Suitable gussets such as designated by the numeral 23 being provided 40 to further support the structure.

45 Referring in particular to Figure 3, in which I have provided for upper and lower tracks. The structure as heretofore described being raised a suitable distance to 50 provide for an under structure consisting of a lower transverse member 25 suitably attached to the inner upright members 10, and further supported by a lower arched or overhead member 26, attached thereto and to

the transverse member 13. The stairways 27 55 being provided, extending from the curb 11 to the lower transverse member 25, and also stairways 28 extending from the lower transverse member 25 to the lower overhead cross walk 29, supported by the lower arched member 26. The ties 30 and the rails 31 for additional tracks being supported on the lower transverse member 25, and tie members 32 re-inforce transverse member 25 as shown on the accompanying drawing. 65

Referring in particular to Figure 2 of the accompanying drawing, in which I have shown the method of elevating the tracks, it being understood that the rolling stock will be stored or "tracked" on the ground level; 70 by means of the elevating tracks 33 suitably supported by upright members 34, and the fence 35 being provided as a means of preventing accidents to trespassers.

Referring to Figure 4, I show a slight 75 modification of my improved elevated railway structure as provided for four tracks. Overhead or diagonal members 36 being provided to support the upper transverse member and the cross walk 18. The ties 21 80 and the rails 22 for the additional tracks being positioned further apart, and located outside the diagonal members 36.

It will be understood that waiting rooms, ticket offices and conveniently located platforms will be provided, as ordinarily used.

It will be further understood that my improved elevated railway structure may be made of fabricated steel, or re-inforced concrete, or a combination of the two. 90

While I have above described the preferred form, construction, and arrangement of the several elements employed, it will be understood that the device is, nevertheless, susceptible of considerable modification therein, 95 and I therefore reserve the privilege of resorting to all such changes as may be fairly embodied within the spirit and scope of the invention as claimed.

Having thus described my invention, what 100 I claim as new and desire to protect by Letters Patent of the United States is as follows:

1. An elevated railway structure comprising a frame work, said frame work supporting two tracks, and consisting of upright members, located at the curb of the street, supporting transverse members, which are 105

- also supported at their extremities by the buildings located at the sidewalk of the said street, re-inforcing arched members having re-inforcing tie members to said transverse members, said arched members also supporting overhead cross walks and stairways, stairways extending from the said sidewalk to the said transverse members, which supports ties and rails for the said two tracks.
- 10 2. An elevated railway structure comprising a frame work, said frame work supporting tracks, and consisting of upright members, located at the curb of the street, supporting transverse members, which are also supported at their extremities by the buildings located at the sidewalk of the said street, overhead members re-inforcing said transverse members with tie members, also supporting overhead cross walks and stairways, stairways extending from the said sidewalk to the said transverse members supporting ties and rails for the said tracks, and an under structure comprising a suitable means of supporting additional tracks.
- 15 3. An elevated railway structure comprising a frame work, said frame work supporting tracks, and consisting of upright members, located at the curb of the street, supporting transverse members, which are also supported at their extremities by the buildings located at the sidewalk of the said street, arch members having tie members re-inforcing said transverse member, and also supporting overhead cross walks and stairways, stairways extending from the said sidewalk to the said transverse members, which supports ties and rails for the said two tracks, and an under structure comprising transverse members reinforced by tie members from over structure, and provided with additional tracks.
- 20 4. An elevated railway structure comprising a frame work so located as not to interfere with street traffic, said frame work supporting tracks, and consisting of upright members, located at the curb of the street, supporting transverse members, which are also supported at their extremities by the buildings located at the sidewalk of the said street, arched members being provided to support overhead cross walks and stairways, said arched members having ties together re-inforcing said transverse members stairways extending from the said sidewalk to the said transverse members, which supports ties and rails for the said tracks, and an under structure suitable for supporting additional tracks, consisting of said lower transverse members attached to inner upright members, and further supported by a lower arched member attached thereto and to the said transverse members re-inforced by tie members, stairways extending from the said curb to the said lower transverse members, stairways extending from the said lower

transverse members to the lower overhead cross walks, supported by lower arched members, ties and rails for the said additional tracks being supported on the said lower transverse members.

5. An elevated railway structure comprising a frame work, said frame work supporting tracks, consisting of upright members, located at the curb of the street, supporting transverse members, which are also supported at their extremities by the buildings located at the sidewalk of the said street, arch members and tie members re-inforcing said transverse members, said arch members supporting overhead cross walks and stairways, stairways extending from the said sidewalk to the said transverse members, which supports ties and rails for the said two tracks, and an under structure suitable for supporting additional tracks, consisting of said lower transverse members attached to inner upright members, and further supported by a lower arched member attached thereto and to the said transverse members, stairways extending from the said curb to the said lower transverse members, stairways extending from the said lower transverse members to the lower overhead cross walks, supported by lower arched members, and ties and rails for the said two additional tracks being supported on the said lower transverse members.

6. An elevated railway structure comprising a frame work, said frame work supporting tracks, consisting of upright members, supporting transverse members, which are also supported at their extremities by the buildings located at the sidewalk of the said street, diagonal and tie members re-inforcing said transverse members said diagonal members supporting overhead cross walks and stairways, stairways extending from the said sidewalk to the said transverse members, which supports ties and rails for the said two tracks, and an under structure comprising a suitable means of supporting additional tracks.

7. An elevated railway structure comprising a frame work so located as not to interfere with street traffic, said frame work supporting two tracks, consisting of upright members, located at the curb of the street, supporting transverse members, which are also supported at their extremities by the buildings located at the sidewalk of the said street, diagonal and tie members re-inforcing said transverse members said diagonal members also supporting overhead cross walks and stairways, stairways extending from the said sidewalk to the said transverse members, which supports ties and rails for the said two tracks, and an under structure suitable of supporting additional tracks, consisting of said lower transverse members attached to inner

upright members, and further supported by a lower diagonal member attached thereto and to the said transverse members, stairways extending from the said curb to the 5 said lower transverse members, stairways extending from the said lower transverse members to the lower overhead cross walks,

supported by lower diagonal members, and ties and rails for the said additional tracks being supported on the said lower transverse 10 members.

In testimony whereof I have affixed my signature.

JOHN CHARLIE KING
